Patented Mar. 9, 1920.

UNITED STATES PATENT OFFICE.

JOHN T. FETHERSTON, OF NEW YORK, N. Y.

LOADING APPARATUS.

1,333,165.

Specification of Letters Patent. Patented Mar. 9, 1920.

Application filed October 17, 1919. Serial No. 331,359.

To all whom it may concern:

Be it known that I, JOHN T. FETHERSTON, a citizen of the United States, residing at 43 West 58th street, New York city, in the county of New York, State of New York, have invented certain new and useful Improvements in Loading Apparatus; and I do hereby declare the following to be a full, clear, and exact description of the invention, such as will enable others skilled in the art to which it appertains to make and use the same.

This invention relates to mechanical loading apparatus particularly adapted for handling material of light weight or composed of loose particles, which, because of these characteristics does not offer sufficient resistance to the movement of a mechanical shovel, scoop, or bucket to permit positive filling thereof by movement through the material. The invention, while capable of employment in handling a wide variety of materials, is especially advantageous in the removal of snow and ice from city streets, the snow and ice being thereby readily lifted and deposited in suitable vehicles for removal.

The invention involves the provision of a loading apparatus, of the movable shovel, scoop or bucket type, having combined therewith a barrier adapted to be moved into the material to be loaded and to serve as a wall for obstructing the movement of the material as the shovel, scoop or bucket is moved into it, thereby positively insuring that the movement of the bucket will cause it to be filled with the material.

A form of loading apparatus which has been extensively used heretofore is that designated as a bucket skimmer excavator consisting of a movable platform, a boom pivotally mounted thereon and projecting therefrom, a bucket depending from and movable upon the boom and mechanism mounted on the platform for propelling the entire apparatus, for moving the bucket along upon the boom to gather the material to be loaded and for turning the boom about its pivot to raise the filled bucket to the dumping position. A skimmer excavator of the character described is commonly employed in loading earth, loose rock or sand on trucks under conditions where the earth, loose rock or sand is to be taken off down to a given level.

Such an excavating and loading appa-

ratus, though well adapted for use in excavating and loading earth, loose rock or sand, is not suitable for use in picking up snow and ice from city streets and loading it upon trucks. This is due primarily to the fact that if the bucket is moved along horizontally over the surface of a paved street to pick up and become filled with snow and ice, the snow and ice is pushed along in front of the bucket and the latter is not filled. By combining with such a loading mechanism a barrier to obstruct the movement of the snow and ice in front of the bucket, this form of loading apparatus is well adapted for handling snow and ice, the bucket and the space between the bucket and the barrier being filled with snow as a result of each movement along the boom toward the barrier. The barrier is preferably constructed in the form of a hood having front and side walls and it is mounted upon the boom near the outer end thereof; preferably the hood is pivotally mounted upon the end of the boom and provision is made whereby it may be moved to and held in any one of a plurality of different positions of adjustment about a horizontal axis, either by a locking device as illustrated in the drawing or by mechanical control of the operator in the cab of the machine.

My invention outlined above may be more fully understood by reference to the accompanying drawings, which illustrate one form in which the invention may be embodied, though it will be understood that the invention may be employed in excavating apparatus varying over a wide range in the construction of its operating parts.

In the drawings, Figure 1 is an elevation of the complete loading apparatus; Fig. 2 is a plan view of the same; Fig. 3 is a section on line 3—3 of Fig. 2; and Fig. 4 is a detail view of the end of the barrier hood.

In the drawings, the loading apparatus is shown as consisting of a platform 5 mounted upon endless multiple belts 6, and an engine 7 mounted on the platform 5 and connected to the belts 6 through suitable gearing whereby the engine 7 may be operated to propel the entire loading apparatus.

A boom 8 is pivotally mounted at 9 upon forward edge of the platform 5. This boom is of any suitable construction but preferably includes two parallel rails forming ways upon which the rollers of a truck 10 are adapted to run, so that the truck 10 may

move upon the boom throughout practically the entire length thereof. This truck 10 carries or forms part of a bucket 11, the body of the bucket being pivoted to the truck 10 at 12. A cable 13 is connected to the truck 10 as hereinafter described and passes over a pulley 14 rotatably mounted upon the outer end of the boom 8; the cable 13 then passes backwardly to a drum 15 mounted on the platform 5 and connected to the engine 7 through suitable gearing so that the engine may be operated to move the bucket 11 upon the boom 8 from the position shown in full lines in Fig. 1 to the position shown in dotted lines. A yoke 25 to which the cable 13 is connected carries two rods 26 supported in suitable guides on the truck 10, and connected by a yoke 27. Springs 28 surround the rods and bear against a shoulder 29 on the truck. Latches 30 are secured to the rods 26 and are adapted to engage shoulders 31 on the bucket 11 to hold the latter in closed position as indicated in Fig. 3. The path through which the bucket moves is governed by the angular position of the boom 8, so that damage to the surface of the street is prevented. To permit of regulating this as desired, the boom is provided with a superstructure 16 to which the end of a cable 17 is secured; this cable 17 passes over one or more pulleys and its end is carried down to one of the winding drums 18 geared to the engine 7. By the operation of this drum by the engine, the boom 8 may be moved to any desired angular position.

Near the outer end of the boom 8, a support 19 is secured to the boom; this support has bearings formed therein for a shaft 20 and the ends of this shaft pass through the side walls of a barrier 21 in the form of a hood having front and side walls as shown. The front wall of the hood is preferably provided with vertically arranged strips 22 which stiffen the metal of this wall and which have their ends extended and sharpened, either directly or by means of removable spikes 22' which may be pointed or blunt, as indicated in Fig. 4. The hood 21 may be rigidly mounted upon the end of the boom 8 in which case its vertical position will be governed wholly by the position of the boom; if desired, however, the hood may be pivotally mounted upon the boom so that its forward edge will be capable of adjustment independent of the boom. For this purpose, I have shown in one form arms 23 projecting from the end of the boom at opposite sides thereof and provided with apertures in their ends. Also, the side walls of the hood 21 are provided with a series of apertures arranged in the arc of a circle about the axis of the shaft 20. A rod 24 may be inserted through any pair of aligned openings in the side walls of the hood and the openings in the ends of the arms 23 to sup-

port the hood in the desired position of angular adjustment about the shaft 20. Other means of adjusting the position of the hood with relation to the boom may be adopted as required.

In operation, the apparatus is propelled to the position where it is to be used by the propelling engine and then, also by operation of the engine, the boom is swung into a horizontal position such that as the bucket 75 is moved along upon the boom its lower edge will move along parallel and close to the roadway which is to be cleared of snow. When the boom is lowered into this horizontal position the edge of the hood cuts 80 into and passes down through the snow so that it lies upon or close to the surface of the roadway. Then the engine is operated to drive the drum 15 and wind upon the cable 13 thereby moving the bucket along 85 upon the boom from the full line to a final position indicated by the dotted line positions shown in Fig. 1. During this movement the hood 21 serves as a barrier to prevent the snow and ice from being pushed 90 along in front and upon opposite sides of the bucket. This obstruction of movement of the snow or ice results in the bucket and the hood being filled with snow or ice by the time it 95 reaches the end of its movement toward the final position on the boom. The engine-driven winding mechanism is then operated to wind up upon the cables 17 and thereby turn the boom about its pivotal connection to the platform so as to raise the outer end of the boom and the bucket and barrier carried thereby. When the bucket and barrier have been raised to the proper height the platform 5 is swung about the 105 axis of its pivotal mounting upon its supporting truck to carry the bucket and barrier over the cart or truck into which the snow and ice is to be loaded. Thereupon the tension on the cable 13 is released permitting the springs 28 to carry the rods 26 and latches 30 rearwardly thereby releasing the bucket which turns about its pivotal axis as indicated in dotted lines in Fig. 1. The load is thus discharged into the underlying 110 vehicle.

Among the advantages of the apparatus is the compression of the snow or ice by the movement of the shovel, scoop or bucket against the barrier. As will be readily appreciated, snow is easily compressed into a much smaller volume than it normally occupies, thus increasing the capacity of the apparatus. The compression of the snow or ice also insures lifting of material occupying 125 the space between the shovel, scoop or bucket and the barrier permitting a further increase in capacity.

Another function and advantage of the barrier is that of anchoring the apparatus 130

on an icy street. The apparatus without anchorage would be moved backwardly as the shovel, scoop or bucket progressed. The barrier when disposed in a pile of snow acts as an anchor and prevents movement of the apparatus.

Various changes may be made in the form and arrangement of the parts without departing from the spirit of the invention and 10 it is to be understood that the word "bucket" in the appended claims is employed to designate a shovel, scoop, bucket or equivalent device.

I claim:

15 1. The combination with a loading apparatus having a bucket, means for moving it to pick up the material to be loaded, and means for lifting the bucket, of a barrier for obstructing movement of the material as 20 the bucket is moved.

2. A loading apparatus comprising the combination of a platform and support mounted thereon and projecting therefrom, a bucket mounted on the support, means for 25 moving the bucket on the support and a barrier mounted on the support for obstructing movement of the material to be loaded as the bucket is moved to gather it.

3. A loading apparatus comprising the 30 combination of a platform, a boom pivotally mounted thereon and projecting therefrom, a bucket mounted on the boom, engine-driven mechanism mounted on the platform for moving the bucket on the boom and for mov- 35 ing the boom about its pivot and a barrier

mounted on the boom for obstructing movement of the material to be loaded as the bucket is moved to gather it.

4. A loading apparatus comprising the combination of a platform, a boom pivotally 40 mounted thereon and projecting therefrom, a bucket movable upon the boom toward and away from the platform, means for discharging the bucket, and a barrier mounted on the outer end of the boom.

45 5. A loading apparatus comprising the combination of a platform, a boom pivotally mounted thereon and projecting therefrom, a bucket mounted on the boom for movement lengthwise thereon, an engine driven 50 mechanism on the platform for moving the bucket and for turning the boom about its pivot, and a hood having end and side walls mounted on the boom near the outer end thereof and operating to obstruct movement 55 of the material to be loaded by the bucket.

6. A loading apparatus comprising the combination of a platform, a boom pivoted thereon and projecting therefrom, a bucket 60 movable on the boom, engine-driven mechanism on the platform for moving the bucket upon the boom and for turning the boom about its pivot, a hood pivotally mounted upon the boom near the outer end thereof and constituting a barrier, and means for supporting the hood in various 65 positions of adjustment about its pivotal connection to the boom.

In testimony whereof I affix my signature.
JOHN T. FETHERSTON.
